COMBINATION SYRINGE, HOT AND COLD PACK APPLIANCE

Filed Nov. 20, 1937

UNITED STATES PATENT OFFICE

2,213,057

COMBINATION SYRINGE, HOT AND COLD
PACK APPLIANCECarl J. Sponsel, Chicago, Ill., assignor to Walgreen
Co., Chicago, Ill., a corporation of Illinois

Application November 20, 1937, Serial No. 175,615

1 Claim. (Cl. 128—403)

This invention relates to therapeutic containers and more particularly to a combination syringe, hot and cold pack appliance, although certain features thereof may be employed with equal advantage in a single purpose rather than a combination therapeutic container.

It contemplates more especially the provision of a novel container closure so as to effectively seal the contents without offering any appreciable obstruction in the use thereof.

Numerous types of combination therapeutic containers have heretofore been proposed, but these have not proven entirely satisfactory for universal use for syringe, hot and cold pack therapeutic purposes. Combination syringe and hot water bottles are common in the art. In rendering such capable of use as an ice pack, there is a requirement for an appreciably larger closure to permit the introduction of solids such as ice. With the increase in size of the closure there necessarily is increased obstruction occasioned by the provision of an orifice to detachably receive the closure for hermetically sealing the contents.

With the teachings of the present invention, the unique arrangement of the stopper or closure enables the usual rubber container body to be utilized without affording any appreciable obstruction as a syringe, hot water and cold ice pack appliance with the same effect as though such was designed specifically for each individual use. Reference to the combination should not be construed as a limitation, since the teachings of the present invention can be employed with advantage on single purpose therapeutic containers.

One object of the present invention is to simplify the construction and improve the operation of devices of the character described.

Another object is to provide an improved combination syringe, hot and cold pack therapeutic container that serves as effectively as any one of these single purpose devices.

Still another object is to provide a novel manner of forming a closure orifice in a substantially flat elongated container of flexible material impervious to water.

A further object is to provide a large closure for detachable connection to a correspondingly formed and complementary orifice that normally is disposed within the body of a substantially flat container without affording any appreciable external obstruction.

Still a further object is to provide a threaded orifice in a substantially elongated flexible con-

tainer for normal disposition within the confines of the walls thereof to receive a substantially flush closure in full engaging position therewith.

A further object is to provide a substantially flat elongated container of flexible material impervious to water with an orifice joined thereto by a reverse fold that serves to normally dispose such within the confines of a container to receive a substantially flush closure for detachable association therewith.

Other objects and advantages will appear from the following description of an illustrative embodiment of the present invention.

In the drawing:

Figure 1 is a plan view of a therapeutic container embodying features of the present invention.

Figure 2 is a front view in elevation of the container shown in Figure 1.

Figure 3 is a sectional view taken substantially along line III—III of Figure 1.

Figure 4 is an enlarged fragmentary sectional view taken substantially along line IV—IV of Figure 1 with the exception that detachable confronting flanges are formed on the container body to serve as a shield for the stopper or tube nipple connection.

Figure 5 is a fragmentary sectional view taken substantially along line V—V of Figure 1 with the exception that the orifice formed in the container has been flexed from its normally collapsed position to more clearly show the integral orifice formation.

The structure selected for illustration comprises a container 10 molded or otherwise shaped from flexible material impervious to water such as rubber that defines a substantially flat elongated container simulating the conventional hot water pack in exterior design. To this end, the top and bottom surface walls 11 and 12, respectively, of the container 10 are of substantially greater expanse than the side edges 13 and 14 which are preferably rounded and of a comparatively narrow depth so far as the dimensional surface expanse of the top and bottom walls 11 and 12. This provides for confining a small quantity of hot or cold medium such as water or ice over the greatest possible area expanse without being unduly heavy in weight to the discomfort of the user.

As shown, the container 10 terminates along a bottom edge 15 in a restricted orifice 16 disposed along a longitudinal median line. The orifice 16 preferably though not essentially comprises a threaded metallic sleeve which is molded, vul-

canized or otherwise joined for permanent connection to the rounded bottom edge 15. Any suitable form of plug or stopper having a metallic shank 17 threaded to correspond with the 5 interior of the sleeve hermetically seals the contents against discharge through the orifice 16. A flexible gasket 18 preferably envelops the threaded plug shank 17 to rest against a closure 19 so as to insure the hermetic sealing against 10 any possible leakage of contents.

The closure 19 preferably terminates in an apertured extremity 20 for connection of a flexible chain 21 thereto so as to anchor the plug 19 to a flap 22 constituting an extension of the top or 15 bottom walls 11 and 12. In the present embodiment, the flap 22 is an extension of the bottom wall 12, the chain 21 being connected thereto by means of a large metallic ring 23. Then, too, another enlarged flap 24 is formed on the 20 container 10 as an extension of the top wall 11 to serve as a hood that shields the stopper or plug 19 against contact with the bare skin of the user.

In the modified embodiment shown in Figure 4, 25 the container 10' is formed with confronting flaps or hoods 22' and 24' of similar configuration and the plug 19' has its connecting chain 21' anchored to a rubber tongue 25 adhesively attached to or molded as an integral part of the interior 30 wall of the lower flap or hood 22', the chain 21' having its enlarged ring extremity 23' projecting therethrough to serve as an anchor therefor. In this manner, the confronting flaps 22' and 24' more effectively serve as shields against any possible 35 contact with the plug 19' when it is in full engaging position with the orifice 16'.

To facilitate the connection and disconnection of the plug 19' or any other attachment for the orifice 16', the confronting hoods 22'-24' are 40 preferably separated by longitudinal edge slits 26 that render such more flexible and capable of separation with ease to accommodate the insertion and removal of the plug 19' or any other appliance that is connected to the orifice 16'. 45 It will be observed that the confronting hoods 22' and 24' terminate in converging arcuate extremities 22" and 24" so that the normal opening defined thereby is somewhat smaller than the plug 19 to insure the utmost protection against 50 contact therewith as such can be extremely hot or cold owing to its metallic construction and the large coefficient of thermal conduction possessed by such materials.

Consequently, when it is desired to use the container 10 as a hot water pack or an ice pack, the plug 19' is fully engaged with the correspondingly threaded orifice 16'. However, should it be desired to utilize the container 10 as a part of a syringe for colonic irrigations, the plug 19' is 55 disengaged from the orifice 16' and a threaded tubular nipple 27 is substituted therefor. The tubular nipple 27 is provided with a threaded shank corresponding to and serving as a complement of the container orifice 16 or 16' while 60 the other extremity has a shank 28 of reduced diameter provided with convolutions or ridges on the exterior peripheral surface thereof to frictionally retain a water conducting tube 29 thereon.

70 The rubber tube 29 leads to any one of different types of syringe tips 30 usually formed of hard rubber. It will be apparent, therefore, that the container can be used as a syringe container or as hot or cold pack as will appear more fully hereinafter. In order to afford the introduction

of solid thermal carrying mediums such as mashed ice and the like, the usual entrant orifice provided on the top edge of rubber bags and the like, cannot be utilized for ice packs. To this end, the top edge 31 of the container 10 is preferably though not essentially provided with a handle member 32 molded or otherwise formed thereon to constitute a wall support or a manual handling expedient.

The handle 32 is preferably formed of rubber 10 that is vulcanized or constitutes an integral part of the container 10 for formation as a one-piece appliance. The entrant orifice of the container 10 is, in this instance, formed in the top wall 11 proximate to the forward or upper edge 31 that is preferably though not essentially elongated outwardly as at 33 along the central portion of the edge 31. This enables the formation of the handle member 32 and accommodates a comparatively large peripheral orifice 34 formed in the wall 11 and connected thereto by a reverse fold 35 to occupy substantially the entire interior depth of the container 10. A metallic sleeve 36 is vulcanized or adhesively joined to the peripheral orifice 34.

The connection of the metallic sleeve 36 with the rubber orifice 34 is accomplished in the present embodiment by a thick fabric liner 37 that is of inverted U-shaped formation (Figure 5) to envelop the edge and sides of the rubber orifice 34 to serve as a reinforcement therefor and as a strong adhesive attaching liner capable of creating a permanent joinder with the external peripheral surface of the metallic sleeve 36 that contacts therewith. As shown, the metallic sleeve 36 has an interiorly formed thread 38 and the top edge thereof is outwardly flanged as at 39 to rest on the edge of the rubber orifice with the adhesive liner 37 disposed therebetween.

The threaded metallic sleeve 36 defining the entrant orifice of the container 10 is of a depth that corresponds with that of the container 10 for normal disposition within the confines thereof between the top and bottom walls 11-12 owing to the reverse fold 35 that connects the metallic sleeve 36 with the wall 11 of the container 10. In consequence thereof, the metallic entrant orifice 34 normally is disposed below the wall 11 of the container 10 so as to receive a correspondingly threaded shank 40 having a substantially flat metallic cap 41 formed thereon. A suitable gasket 42 envelops the closure shank 40 so as to serve as a seat against the flanged peripheral edge 39 of the metallic entrant orifice sleeve 36, thereby effectively sealing the contents against leakage when the cap 41 has its shank 40 fully engaged with the entrant orifice sleeve 36. To this end, the closure 41 has its edge knurled as at 43 to facilitate the engagement and disengagement between the threads 38-40 on the sleeve 36 and shank 40, respectively.

It will be noted that the closure cap 41 is only slightly arcuate to present a substantially flat surface that will lie almost flush with the top wall 11 of the container 10, thereby providing negligible or no obstruction in the normal use of the container 10 as a hot water pack or cold ice pack appliance. To fill the container 10, it is only necessary to remove the closure cap 41 and displace the orifice sleeve 36 upwardly beyond the normal confines of the container 10. This is rendered possible by the reverse fold 35 (see Figure 5) so that ice, water or other thermal carrying mediums may be incorporated therein depending upon the use or purpose for which the

container 10 is to be utilized at any particular time.

After the container 10 has been properly filled to the desired capacity (preferably not full capacity), the closure cap 41 is fully engaged with the sleeve 36 and permitted to assume the position within the confines of the container 10 (Figures 1, 2 and 3) so that it can be utilized as a hot water pack or cold pack without the closure 41 providing any appreciable obstruction and yet affording a sufficiently large opening to readily admit solid as well as liquid contents. While forming no part of the invention, it is advantageous to provide a closure anchoring chain 43 for 10
